(57) **CLAIM**

The ornamental design for a levitation base, as shown and described.

DESCRIPTION

FIG. 1 is a front and bottom perspective view of a levitation base showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a bottom plan view thereof;

FIG. 7 is a top plan view thereof; and,

FIG. 8 is a front and bottom perspective view thereof, shown in use with a levitated object.

The broken lines in the drawings depict the portions of the levitation base that form no part of the claimed design.

The broken lines showing the levitated object in FIG. 8 depict environmental subject matter that forms no part of the claimed design.

1 Claim, 6 Drawing Sheets
